UNITED STATES PATENT OFFICE.

ALFRED L. EUSTICE, OF CHICAGO, ILLINOIS.

INCLOSED ELECTRIC FUSE.

Application filed June 21, 1918. Serial No. 241,115.

To all whom it may concern:

Be it known that I, ALFRED L. EUSTICE, a citizen of the United States, residing at Chicago, in the county of Cook and State of Illinois, have invented certain new and useful Improvements in Inclosed Electric Fuses, of which the following is a specification.

This invention relates to inclosed electric fuses in which a shell or housing is provided with an end-closure, that also serves for holding a terminal in place, and has for its object to provide a combined gas-check and terminal-lock end-closure that will facilitate repeated removal and replacing of the parts in proper relations one to the others, and thereby adapt the fuse to be used as a renewable fuse.

The several features of the invention may be realized in a number of different constructions differing among themselves in details, some of which are illustrated in the accompanying drawings, in which—

Fig. 1 is an external view of a complete fuse with one of the two similarly constructed ends in section, and showing one embodiment of the several features of the invention;

Fig. 2 is an axial section of one end of the fuse, the shell with its tubular attaching head as preferably employed in all embodiments of the invention, shown in perspective;

Fig. 3 is a perspective view of the combined gas-check and terminal-lock employed in Fig. 1;

Fig. 4 is a detailed view of the blade terminal employed in Fig. 1;

Fig. 5 shows a modified form of locking disk;

Fig. 6 is a detailed view of the ferrule, preferably employed in all of the forms;

Figs. 7 and 7^a show by opposite perspective views a modified construction of gas-check or locking disk;

Figs. 8 and 8^a show by two longitudinal sections a further modification of the construction and assembly of terminal blade and disk;

Fig. 9 is a perspective view showing a further modification of the combined gas-check and terminal-lock;

Fig. 10 shows the terminal preferably employed with the disk of Fig. 9;

Figs. 11, 11^a and 11^b show, by plan and

two edge views, a further modification of the combined gas-check and terminal-lock;

Figs. 12 and 12^a are views of a modified form of terminal and a sealing washer adapted to be counter-sunk into the outer shoulder thereof, and which may be employed in connection with the sealing and locking device of Figs. 11 and 11^b; and

Fig. 13 shows in section, and Figure 13^a shows in edge elevation the devices of Figs. 11 to 12^a assembled.

One object of the present invention is to adapt a tubular shell made of suitable insulating material, such as indurated fiber, to receive the gas-check and terminal-lock end-

closure, and to serve indefinitely in connection therewith, as a housing for renewable fuses, to which end a tubular body 1, of insulating material, is provided with a tubular head 2 of metal, formed with a reduced portion 2^a screw-threaded into the body and forming a bushing therein to resist shrinkage, and with a larger portion 2^b affording a seat and centering guide 2^c for any of the end-closures disclosed herein; the portions

2^a and 2^b being offset by a shoulder 2^d which adapts the head to abut against the body

1. Notches 2^e receive corresponding portions of the end-closure to interlock therewith and prevent rotation of the end-closure and the terminal blade upon the head,

and the external threads 2^f upon the enlarged portion 2^b of the head provide for removable attachment of the ferrule 5,

which is to confine the end-closure and the parts which it controls.

The end-closure 3 may take any one of a number of forms, several of which are illustrated herein. In connection with each,

the object is to provide a convenient means for embracing and detachably interlocking with the terminal 4, and through which the terminal may be centered upon and firmly anchored to the shell 1, and which, notwithstanding these functions, will afford a substantially impervious wall over the end of

the shell. To these ends, and for the fullest realization of all the advantages of my invention, all forms of the combined gas-check

and terminal lock have, as their principal characteristics, a disk 3, separable or opening up at the terminal into a pair of complementary members 3^a and 3^b recessed to 5 receive the terminal between them, conforming to apertures, shoulders, or other reduced portions of the terminal in a manner to interlock with the terminal and prevent both rotation and longitudinal movement thereof, said disk fitting snugly upon 10 the terminal in a manner to check the passage of gas between the terminal and disk, so seated upon the head 2 and held to the notches 2^e thereof as to prevent rotation of 15 the disk upon the head, and also affording a continuous end wall for the housing, and presenting a continuous outer surface to the wall of the ferrule 5 which presses against it so that the gas developed in the blowing 20 of the fuse is effectively checked against discharge longitudinally beyond the disk, and is diverted to the elongated relief passages afforded by the screw threads 5^b within the ferrule. The invention is, however, not 25 limited to the embodiment of all these characteristics in a single structure, but may be measurably realized by various sub-combinations thereof, as pointed out in the subjoined claims. The claims, therefore, should 30 be looked to to ascertain the scope of the invention as well as the novel details of construction embraced within it.

Referring more particularly to the several disclosed embodiments of the invention.

35 The terminal 4 of all the figures has the shoulders 4^a which are interlocked by the disk 3 in the direction to resist inward thrust of the terminal. In Figs. 4 and 10, the terminal is further provided with the 40 eye 4^b that receives intermediate projections 3^c on the members 3^a and 3^b of the disk, which projections meet within the eye and interlock with the terminal in a manner to resist displacement thereof in both axial 45 directions.

In Fig. 9 one of the projections 3^c has half of its thickness continued to provide a bridging extension 3^d, from the member 3^a, that underlies the member 3^b and reaches 50 the opposite wall of the shell, thereby insuring increased steadiness of the terminal support.

In Fig. 4 the terminal is provided with a fixed flange 4^e that underlies the disk 3 in 55 a manner to confine the disk between the flange and the shoulders 4^a, and thereby afford increased bearing between the parts and provide an inner seal for the joints between the disk and terminal. Flange 4^e, if, 60 as preferred, made to fit the tubular head, further serves to center the terminal 4 in the shell 1 during assembly, and to afford a bulk head to arrest finely-divided material at one end while it is being introduced at the 65 opposite end.

According to Figs. 3 and 5, the ends of the joint between the members 3^a and 3^b are lapped at 3^e to assist in sealing the joint and to miter the parts together against displacement.

70 In Figs. 9 and 11, the members 3^a, 3^b, are assembled by halving joints, Fig. 9 showing the end walls of the terminal recess provided with extensions 3^f underlying the member 3^b, and of a thickness complementary to that of the latter so that the upper strata alone are complementary as to the area of the disk, and Figs. 11-11^b showing each of the members, 3^a, 3^b, provided with half laps 3^g upon the other at the ends of 80 the terminal recess.

Again, the members 3^a, 3^b, may be wholly separable, as shown in Fig. 5, and the surrounding ferrule alone relied upon to hold them together around the terminal; or connected together by hinges 3^h, as shown in Figs. 7, 7^a, Fig. 9, and Figs. 11-11^b; or limited in their separation by slot and pin connections 3ⁱ, as shown in Fig. 3. And in so connecting the members of the disk, they 90 may be hinged directly, one to the other, as suggested in Figs. 9 and 11, or through the medium of a base member 6, Figs. 7, 7^a, essentially in the form of a ring having an enlargement 6^a providing a gate to receive 95 the wider portion of the terminal in assembling and with a reduced opening 6^b confining the terminal edgewise while the members 3^a, 3^b, closed upon the blade, confine it laterally; or the connection of the members 100 3^a, 3^b may be through the medium of a base member 7 in the form of an outer sealing washer, as shown in Fig. 3, upon which are provided one portion, for instance, the pins, of the slot and pin connections 3ⁱ, and in 105 which is formed a terminal opening 7^a snugly fitting the larger dimensions of the terminal. Washer or base member 7, being continuous, overlaps the joints between members 3^a and 3^b and checks the escape of 110 gas therethrough. It also presents a smooth outer surface to receive the confining flange of the ferrule, and better enables the ferrule to pack the end-closure.

The inner sealing flange 4^e and outer sealing washer 7 will ordinarily be employed only for larger capacity fuses, and to still further safeguard against leakage, a soft packing member 8, of leather or other material equivalent for the purpose, may be 115 interposed between the disk members 3^a, 3^b, and the base member 7.

It is not necessary in all instances to have the inner flange on the terminal or the eye therein. As suggested in Figs. 8 and 8^a 120 longitudinal interlocking in the outward direction may be insured by fitting the disk 3 into a groove 4^d in one or more faces of the terminal; or, as suggested in Figs. 12 and 13, additional shoulders 4^e may be suitably 130

spaced beneath the shoulders 4^a to receive the disk between them. In this arrangement the fixed flange 4^c is used as in Figures 1, 3, and 4. The form of terminal 4 shown in Figures 8 and 8^a is also suitable for use in connection with the form of disk shown in Figures 7 and 7^a.

As further suggested in Figs. 12 and 12^a, an upper sealing and sustaining washer 9 may be employed with an opening 9^a sufficient to pass the shoulders 4^a, as by tipping the washer over them successively, and this washer may be embedded in the under faces of the upper shoulders 4^a, and thus avoid the necessity of extending the upper washer out to the engaging wall of the ferrule. In all cases, lugs 10 are preferably located on the disk to enter the recesses 2^e and hold the disk and its associated parts from turning on the shell.

The ferrule 5, in each instance, is preferably provided with an internal engaging wall 5^a through which it clamps the disk and its associated parts upon the end of the shell; also with internal threads 5^b through which it engages the external threads of the shell (provided by the tubular head). But the ferrule does not terminate with its threaded portion 5^b, but extends beyond the same in a lip or apron 5^c that provides a baffle for the gases and insures their direction along the wall of the shell instead of outward. The device effectually prevents end discharge of gases.

The probable course of the gases of blowing is through notches 2^e to the thread spaces of the ferrule and thence through the circuitous passage so provided to the space beneath the baffle or apron of the ferrule.

What I claim is:

1. In an electric fuse having a shell and a link-supporting terminal; a combined gas-check and terminal-lock end-closure therefor, comprising a ferrule and a disk surrounding the terminal and clamped between a wall of the ferrule and the end of the shell; said disk comprising a pair of separable complementary members meeting at the terminal, interlocking with the terminal to resist relative rotary and longitudinal movement thereof, and constructed to provide a continuous end wall for the shell and a continuous surface through which the disk receives the clamping wall of the ferrule, whereby it confines the escape of gas mainly to the spaces within the disk and ferrule.

2. In an electric fuse having a shell and a link-supporting terminal; a combined gas-check and terminal-lock end-closure therefor, comprising a ferrule and a disk surrounding the terminal and clamped between a wall of the ferrule and the end of the shell; said disk comprising a pair of separable complementary members meeting

at the terminal, having an interlock with the shell to resist rotation thereon and said terminal having an interlock with the disk to resist both rotary and longitudinal relative movement between them; said disk being constructed to provide a continuous end wall for the shell and a continuous surface through it receives the clamping wall of the ferrule whereby it confines the escape of gas mainly to the spaces within the disk and ferrule.

3. In an electric fuse having a shell and a link-supporting terminal; a combined gas-check and terminal-lock end-closure therefor, comprising a ferrule and a disk surrounding the terminal clamped between a wall of the ferrule and the end of the shell; said disk comprising a pair of separable complementary members meeting at the terminal, having lug and notch interlock with the shell to resist its rotation thereon, and vent the fuse through the wall of the shell within the ferrule, and said terminal having an interlock with the disk to resist both rotary and longitudinal relative movement between them; and said disk being constructed to provide a continuous end wall for the shell and a continuous surface through which it receives the clamping wall of the ferrule whereby it confines the escape of gas mainly to the spaces within the disk and ferrule.

4. In an electric fuse having a shell and a link-supporting terminal, a combined gas-check and terminal-lock end-closure therefor, comprising a ferrule and a disk surrounding the terminal and clamped between a wall of the ferrule and the end of the shell; said disk comprising a pair of separable complementary members meeting at the terminal, and said terminal having a reduced and shouldered portion through which it receives the members of the disk and provides an interlock therewith to resist both rotary and longitudinal relative movement; and said disk being constructed to provide a continuous end wall for the shell and a continuous surface through which it receives the clamping wall of the ferrule whereby it confines the escape of gas mainly to the spaces within the disk and ferrule.

5. In an electric fuse having a shell and a link-supporting terminal; a combined gas-check and terminal-lock end-closure therefor, comprising a ferrule and a disk surrounding the terminal and clamped between a wall of the ferrule and the end of the shell; said disk comprising a pair of separable complementary members meeting at the terminal, and said terminal having a reduced and shouldered portion through which it receives the members of the disk and provides an interlock therewith to resist both rotary and longitudinal relative movement, the shoulders of the terminal over-lying and sealing the meeting faces of the disk mem-

- bers; and said disk being constructed to provide a continuous end wall for the shell and a continuous surface through which it receives the clamping wall of the ferrule whereby it 5 confines the escape of gas mainly to the spaces within the disk and ferrule.
6. In an electric fuse having a shell and a link-supporting terminal; a combined gas-check and terminal-lock end-closure there- 10 for, comprising a ferrule and a disk surrounding the terminal and clamped between a wall of the ferrule and the end of the shell; said disk comprising a pair of separable complementary members meeting at the 15 terminal, and said terminal having a reduced and shouldered portion through which it receives the members of the disk and provides an interlock therewith to resist both rotary and longitudinal relative movement,
- 20 the shoulders of the terminal over-lying and sealing the meeting faces of the disk members; a sealing washer being fitted snugly around the terminal on one side of the disk and overlying and sealing that portion of 25 the meeting faces of the disk members which extend beyond the terminal; said disk being constructed to provide a continuous end wall for the shell and a continuous surface through which it receives the clamping wall 30 of the ferrule whereby it confines the escape of gas mainly to the spaces within the disk and ferrule.
7. In an electric fuse having a shell and a link-supporting terminal; combined gas- 35 check and terminal-lock end-closure there- for, comprising a ferrule and a disk surrounding the terminal clamped between a wall of the ferrule and the end of the shell; said disk comprising a base member and a 40 pair of complementary members movably mounted upon said base member and meeting at and interlocking with the terminal to resist relative rotary and longitudinal movement thereof; and said disk being constructed to provide a continuous end wall for the shell and a continuous surface through 45 which it receives the clamping wall of the ferrule whereby it confines the escape of gas mainly to the spaces within the disk and ferrule.
- 50 8. An end-closure for inclosed fuses, having blade terminals, comprising a base member constructed with an opening to admit the terminal end-wise, and a divided locking disk having its members separable to admit the terminal between them, and having pro- 55 jections for entering recesses of the terminal to interlock the end-closure therewith; the members of the disk having slot and pin 60 connections with the base member whereby they are permanently mounted thereon.
- 65 9. In an electric fuse having a shell and a link-supporting terminal; a terminal-lock, comprising a disk composed of a pair of separable complementary members meeting 70 at the terminal, interlocking with the terminal to resist relative movement thereof, and a circular shoulder secured to the terminal underneath the terminal lock, and substantially fitting the bore of the shell, and thereby serving as a bulk-head for finely-divided filling material while the latter is being inserted.
- 75 10. A combined end-closure and terminal lock for inclosed fuses, comprising a base member having permanently mounted thereon a disk divided into relatively movable parts meeting adjacent the terminal, recessed to permit them to receive and close upon the terminal, and having connections 80 with the base member which guide them into proper meeting relation and leave the meeting portions of the disk beyond the edges of the terminal lapped by the base member.
- 85 11. In an electric fuse having a shell and a terminal, a disk for positioning the terminal upon the shell, comprising a plurality of complementary parts permanently connected together but relatively movable trans- 90 versely to the longitudinal axis of the terminal for interlocking the disk with and dis- 95 engaging it from the terminal.
- 100 12. In a fuse having a shell and a blade terminal, a disk for positioning the terminal upon the shell comprising a base member and a locking member permanently connected with and carried by said base member and movable thereon into and out of engagement with the terminal to prevent separation of the base member therefrom.
- 105 13. In a fuse having a shell and a blade terminal, a disk for positioning the terminal upon the shell comprising a base member and a locking member permanently connected with and carried by said base member and movable thereon into and out of engagement with the terminal to prevent separation of the base member therefrom; said base member surrounding the terminal and being assembled therewith by longitudinal 110 movement relatively thereto.
- 115 14. In a fuse having a shell and a blade terminal, a disk for positioning the terminal on the shell comprising a base member assembled with the shell by movement longitudinally thereof, and a pair of comple- 120 mentary disk members permanently connected with and carried by said base member and movable thereon transversely of the longitudinal axis of the terminal to interlock and release the latter.
- 125 15. In a fuse having a shell and a blade terminal, a disk for positioning the terminal on the shell comprising a base member assembled with the shell by movement longitudinally thereof, and a pair of comple- 130 mentary disk members permanently connected with and carried by said base member and movable thereon transversely of the longitudinal axis of the terminal to interlock

and release the latter; the opposed edges of said complementary disk members engaging said terminal both longitudinally and rotarily.

5 16. In an electric fuse having a shell and a link supporting terminal; an end-closure therefor, comprising a ferrule and disk surrounding the terminal and clamped between a wall of the ferrule and the end of the 10 shell; said disk comprising a pair of sep-

arable complementary members meeting at the terminal, interlocking with the terminal to resist relative rotary and longitudinal movement thereof, and an enlarged shoulder fixed to the terminal on the under side of 15 the end-closure, and sealing the meeting faces of the disk.

Signed at Chicago, Illinois, this 17th day of June, 1918.

ALFRED L. EUSTICE.
